AZO DYES

Swanie S. Rossander, Wilmington, Del., assignor
to E. I. du Pont de Nemours & Company, Wil-
mington, Del., a corporation of Delaware

No Drawing. Application January 23, 1937,
Serial No. 122,011

REISSUED

JUN 4 1940

8 Claims. (Cl. 260—159)

A. This invention relates to azo dyestuffs and to material of organic fibrous origin dyed with the new dyestuffs, and to processes of producing the dyes and of dyeing. The invention will be described with reference to particular examples but this description is to be taken as exemplary, not 5 limitative.

B. It is an object of the invention to dye cotton and regenerated cellulose particularly, and also 10 wool, leather, and organic derivatives of cellulose, such as the cellulose esters and ethers, by processes which yield on cotton and regenerated cellulose dyeings of outstanding fastness to washing. Other objects of the invention will be to 15 produce the new dyes and dyed products by processes which are economically and technically satisfactory.

C. The objects of the invention are accomplished, generally speaking, by diazotizing the 20 compounds produced in our copending application Serial Number 122,030, filed of even date herewith, and coupling thereto azo dyestuff developing agents such as beta naphthol, pyrazolone, 2:4-dihydroxy quinoline, meta tolylene di-

the arrows point. The symbol PAB means para-amino-benzoyl and the symbol MAB means meta-amino-benzoyl.

Example I

Five parts of cotton piece goods were dyed in the usual manner known to those in the art with ten-hundredths part of (1-methoxy-phenyl-3-methyl-5-pyrazolone)₂ Di (para-amino-benzoyl) 1:3-diamino benzene-4-sulfonic acid. The dyed fabric (yellow in color) was rinsed in cold water and put in a casserole with 200 parts of water at 20° C. Three-tenths part of sodium nitrite and four-tenths part of sulfuric acid were 10 added. The whole was stirred 15 minutes and rinsed with cold water. One-tenth part of 1-phenyl-3-methyl-5-pyrazolone was dissolved in 200 cc. water and one-tenth part of soda ash. The solution was stirred rapidly while adding the 20 above rinsed piece goods and then stirred slowly for 15 minutes and rinsed in cold water and dried. The dyeing was a bright greenish yellow in shade. The formula of the dye on the fiber is:

25

5

10

15

20

25

35

amine, and aceto acetanilide. The objects of the 40 invention are accomplished in a preferred form by dyeing the material with the products of the said identified application, subjecting the dyed fiber to a diazotization process and coupling it to the selected developing agent. Preferred re- 45 sults are sometimes obtained by the use of beta naphthol and 1-phenyl-3-methyl-5-pyrazolone. It will be found that dyestuffs possessing ortho amino azo groups on the N components are not generally diazotizable and are, consequently, not 50 satisfactory for use in this invention.

D. The invention will be more fully comprehended by reference to the examples, in the table of which the arrows indicate that the preceding compound is diazotized and coupled to the indicated equivalents of the compounds to which

Example II

Five parts of cotton piece goods were dyed in the usual manner known to those skilled in the art with two hundredths part of di(para amino benzoyl) meta phenylene diamine₂ (J-acid)₂. The dyed fabric (red in color) was rinsed in cold water and put in a casserole with 200 parts of water at 20° C. Three tenths part of sodium nitrite and four tenths part of sulfuric acid were added. The whole was stirred 15 minutes and rinsed with cold water. One tenth part of 2-naphthol was dissolved in 200 parts of water and one twentieth part of caustic soda. The solution was stirred rapidly while adding the above rinsed piece goods. The mass was stirred for 15 minutes, rinsed in cold water and dried. The 55

dyeing was a bright Bordeaux shade. The formula of the dye on the fiber is:

Example III

15 Five parts of cotton piece goods were dyed in the usual manner known to those skilled in the art with two hundredths part of di(meta amino benzoyl) 1 - 3 - diamino - benzene - 4 - sulfonic acid $\Rightarrow$ (meta amino benzoyl J-acid) $_2$. The dyed fabric (orange in color) was rinsed in cold water and put in a casserole with 200 parts of water at 20° C. Three tenths part of sodium nitrite and

of water at 20° C. Three tenths part of sodium nitrite and four tenths part of sulfuric acid were

added. The whole was stirred 15 minutes and rinsed with cold water. One tenth part of 2-naphthol was dissolved in 200 parts of water and one-twentieth part of caustic soda. The solution was stirred rapidly while adding the above rinsed piece goods. The mass was stirred for 15 minutes, rinsed in cold water and dried. The dyeing was a bright yellow orange shade. The formula of the dye on the fiber is:

40 four tenths part of sulfuric acid were added. The whole was stirred 15 minutes and rinsed with cold water. One tenth part of 2-naphthol was dissolved in 200 parts of water and one twentieth part of caustic soda. The solution was stirred rapidly while adding the above rinsed piece goods. The mass was stirred for 15 minutes, rinsed in cold water and dried. The dyeing was a bright orange shade. The formula of the dye on the fiber is:

Example V

45 8 parts of (1-methyl-amino-phenyl-3-methyl-5-pyrazolone) $\Rightarrow$ di(para - amino - benzoyl) 1:3 - diamino benzene-4-sulfonic acid were slurried with 300 parts of water. 2 parts of caustic soda were added and warmed to solution and then cooled to 20° C. 2 parts of sodium nitrite were added and the whole was dumped in 5 parts of hydrochloric acid (100%) and stirred for 3 hours, maintaining

Example IV

70 Five parts of cotton piece goods were dyed in the usual manner known to those skilled in the art with two hundredths part of di(para amino benzoyl) 1-3-diamino benzene-4-sulfonic acid $\Rightarrow$ (1-methyl amino phenyl-3-methyl-5-pyrazolone) $_2$. The dyed fabric (yellow in color) was rinsed in cold water and put in a casserole with 200 parts

75 acidity to Congo red and a distinct excess of sodium nitrite.

70 5 parts of beta naphthol were slurried with 200 parts of water. Approximately 1.4 parts of caustic soda were added and warmed to solution, distinctly alkaline to brilliant yellow paper. The whole was cooled to 20° C. 10 parts of soda ash were added and stirred until dissolved. The

tetrazo prepared in the above paragraph was slowly added and the mass stirred three hours, maintaining a distinct excess of beta naphthol and alkalinity on brilliant yellow paper. The whole was warmed to 75° C., filtered, and dried at 5

stirred 3 hours, keeping an excess of 1-phenyl-3-methyl-5-pyrazolone and red alkalinity on brilliant yellow paper. The mass was warmed to 70° C., filtered, and dried at 90-100° C. The formula of the dye is: 5

90°-100° C. The dried powder was yellow. The formula of the dye is:

Example VII
Five parts of cotton piece goods were dyed in

Example VI

11 parts of (para-amino-benzoyl J-acid)₂ di (para-amino-benzoyl) 1:3-diamino benzene-4-sulfonic acid were slurried with 300 parts of 50 water. 2 parts of caustic soda were added and warmed until dissolved. The whole was cooled to 20° C. and 2 parts of sodium nitrite were added. The mass was dumped in 5 parts of hydrochloric acid (100%) and stirred for 3 hours, maintaining 55 an acidity to Congo red and distinct excess of sodium nitrite.

5 parts of 1-phenyl-3-methyl-5-pyrazolone soda were slurried and stirred at 20° C. until dissolved. 10 parts of soda ash were added and stirred until 60 dissolved. The tetrazo prepared in the above paragraph was slowly added. The mass was

the usual manner known to those in the art with 45 four-hundredths part of (para-amino-benzoyl J-acid)₂ di (para-amino-benzoyl) 1:3-diamino benzene-4-sulfonic acid. The dyed fabric (orange in shade) was rinsed in cold water and put in a 50 casserole with 200 parts of water at 20° C. Three-tenths part of sodium nitrite and four-tenths part of sulfuric acid were added. The whole was stirred 15 minutes and rinsed with cold water. One tenth part of 2 naphthol was dissolved in 200 55 parts water and one twentieth part of caustic soda. The solution was stirred rapidly while adding the above rinsed piece goods. The mass was stirred for 15 minutes, rinsed in cold water and dried. The dyeing was a bright orange shade. 60 The formula of the dye is:

In the following tables procedures similar to the foregoing were employed.

	Diazo component	Coupling component	Shade on cotton
8	Di(para-amino-benzoyl) 1:3-diamino benzene → ((para-amino-benzoyl) J-acid);	Beta naphthol 1-phenyl-2-methyl-5-pyrazolone Aceto acetanilide Meta tolylene diamine 2:4-dihydroxy quinoline	Orange. Scarlet. Do. Dull scarlet. Orange.
10	Di(para-amino-benzoyl) 1:3-diamino benzene → ((meta-amino-benzoyl) J-acid);	Beta naphthol	Do.
10	Di(para-amino-benzoyl) 1:3-diamino benzene → (J-acid);	do	Bordeaux.
11	Di(para-amino-benzoyl) 1:3-diamino benzene → (1-meta-amino-phenyl-5-pyrazolone-3-carboxylic acid);	do 1-phenyl-3-methyl-5-pyrazolone	Orange. Yellow.
15	Di(para-amino-benzoyl) 1:3-diamino benzene → ((para-amino-benzoyl) J-acid) (1-meta-amino-phenyl-5-pyrazolone-3-carboxylic acid)	Beta naphthol 1-phenyl-3-methyl-5-pyrazolone 2:4 dihydroxy quinoline Meta phenylene diamine Aceto acetanilide	Orange. Yellow. Orange. Yellow. Do. Yellow brown. Yellow.
18	Di(para-amino-benzoyl) 1:3-diamino benzene → (Di(para-amino-benzoyl) 3:5-diamino benzoyl J-acid);	Beta naphthol	Orange.
20	Di(para-amino-benzoyl) 1:4-diamino benzene → J-acid	do	Bordeaux.
15	Di(para-amino-benzoyl) 1:4-diamino naphthalene → ((meta-amino-benzoyl) J-acid);	do	Orange.
25	Di(para-amino-benzoyl) 1:4-diamino naphthalene → ((para-amino-benzoyl) J-acid);	do	Do.
17	Di(para-amino-benzoyl) 1:4-diamino naphthalene → (1-meta-amino-phenyl-5-pyrazolone-3-carboxylic acid);	Beta naphthol 1-phenyl-3-methyl-5-pyrazolone	Do. Yellow.
30	Di(para-amino-benzoyl) 1:3-diamino benzene-4-sulfenic acid → (1-meta-amino-phenyl-5-pyrazolone-3-carboxylic acid);	Beta naphthol 2:4-dihydroxy quinoline Aceto acetanilide 1-phenyl-3-methyl-5-pyrazolone Meta tolylene diamine	Orange. Yellow. Do. Do. Yellow brown.
19	Di(para-amino-benzoyl) 1:3-diamino benzene-4-sulfonic acid → ((meta-amino-benzoyl) J-acid);	Beta naphthol	Orange.
35	Di(para-amino-benzoyl) 1:3-diamino benzene-4-sulfonic acid → ((para-amino-benzoyl) J-acid);	do	Do.
21	Di(para-amino-benzoyl) 1:3-diamino benzene-4-sulfonic acid → (1-meta-amino-phenyl-3-methyl-5-pyrazolone);	Beta naphthol 1-phenyl-3-methyl-5-pyrazolone Aceto acetanilide 2:4-dihydroxy quinoline	Orange. Yellow. Do. Do. Yellow brown.
40	Di(para-amino-benzoyl) 1:3-diamino benzene-4-sulfonic acid → (1-meta-amino-phenyl-5-pyrazolone-3-carboxylic acid) ((para-amino-benzoyl) J-acid);	Beta naphthol	Orange.
23	Di(para-amino-benzoyl) 1:3-diamino benzene-4-sulfonic acid → (meta toluidine);	do	Do.
24	Di(para-amino-benzoyl) 1:3-diamino benzene-4-sulfonic acid → (Di(para-amino-benzoyl) 3:5-diamino benzoyl J-acid);	do	Do.
45	Di(para-amino-benzoyl) 1:3-diamino benzene-4-sulfonic acid → (Di(para-amino-benzoyl) 3:5-diamino benzoyl J-acid);	1-phenyl-3-methyl-5-pyrazolone	Yellow orange.
26	Di(para-amino-benzoyl) 1:4-diamino benzene-6-sulfonic acid → ((para-amino-benzoyl) J-acid);	Beta naphthol	Orange.
50	Di(para-amino-benzoyl) 1:4-diamino benzene-6-sulfonic acid → ((meta-amino-benzoyl) J-acid);	do	Do.
28	Di(para-amino-benzoyl) 1:4-diamino benzene-6-sulfonic acid → (1-meta-amino-phenyl-5-pyrazolone-3-carboxylic acid);	Beta naphthol 1-phenyl-3-methyl-5-pyrazolone	Do. Yellow.
29	Di(para-amino-benzoyl) 1:4-diamino benzene-6-sulfonic acid → (1-meta-amino-phenyl-3-methyl-5-pyrazolone);	Beta naphthol 1-phenyl-3-methyl-5-pyrazolone	Orange. Yellow.
55	Di(para-amino-benzoyl) 1:4-diamino benzene-6-sulfonic acid → (J-acid);	Beta naphthol	55
31	Di(meta-amino-benzoyl) 1:3-diamino benzene-4-sulfonic acid → ((meta-amino-benzoyl) J-acid);	do	Bordeaux.
60	Di(meta-amino-benzoyl) 1:3-diamino benzene-4-sulfonic acid → ((para-amino-benzoyl) J-acid);	do	Orange.
33	Di(meta-amino-benzoyl) 1:3-diamino benzene-4-sulfonic acid → (1-meta-amino-phenyl-5-pyrazolone-3-carboxylic acid);	Beta naphthol 1-phenyl-3-methyl-5-pyrazolone 2:4-dihydroxy quinoline Aceto acetanilide Meta phenylene diamine	Orange. Yellow. Do. Do. Red brown.
65	Di(meta-amino-benzoyl) 1:3-diamino benzene-4-sulfonic acid → (1-meta-amino-phenyl-3-methyl-5-pyrazolone);	Beta naphthol Meta tolylene diamine 1-phenyl-3-methyl-5-pyrazolone 2:4-dihydroxy quinoline Aceto acetanilide	Orange. Orange. Red brown. Red brown. Yellow.
35	Di(para-amino-benzoyl) 1:3-diamino benzene-4-sulfonic acid → (1-meta-amino-phenyl-5-pyrazolone-3-carboxylic acid);	Beta naphthol 1-phenyl-3-methyl-5-pyrazolone	Orange. Yellow.
70	Di(para-amino-benzoyl) 1:3-diamino benzene → (1-meta-amino-phenyl-5-pyrazolone-3-carboxylic acid);	Beta naphthol 1-phenyl-3-methyl-5-pyrazolone	Orange. Yellow.

F. The products of the invention may be produced on the fiber or in isolated form. Coupling nuclei in which coupling takes place adjacent to an hydroxy or amino group. The

azo components are represented by the formula:

5 in which R comprises a benzene nucleus, R₁ comprise aryl nuclei, and R₂ comprise benzene, naphthalene or pyrazolone nuclei.

10

15 G. There may be substituted on the various nuclei of the invention substituent groups from the list alkyl, alkoxy, halogen, aryloxy, aralkyl, aralkoxy, aryl, hydroxyloxy, trifluoro-alkyl, hydroxyl sulfonic acid and carboxyl, in which each R is a radical of a primary aryl-amine of the group consisting of an amino naphthol sulfonic acid, 1-meta-amino-phenyl-5-pyrazolone-3-methyl, and 1-meta-amino-phenyl-5-pyrazolone-3-carboxyl, and Y is one of a group
